UNITED STATES PATENT OFFICE

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY

SOOT CLEANER FOR BOILERS

Application filed June 18, 1923. Serial No. 646,031.

It has heretofore been suggested that soot-cleaning elements be provided with plain jet openings through which fluid under pressure is ejected for the purpose of cleaning soot from boiler tubes. Tubes commonly employed for this purpose, however, are not of sufficient thickness to form a satisfactory jet opening. Furthermore, the material from which such tubes are made is necessarily 5 comparatively soft, with the result that the high pressure fluid ejected from the jet openings quickly erodes the wall surrounding the openings, thereby destroying the utility of the tubes. In an attempt to overcome this 10 difficulty, the soot-blowing element has been provided with small tubular members constituting nozzles connected to openings in the tubes and projecting therefrom. Such an arrangement makes an unsymmetrical device. 15 The heat radiation from the projecting nozzles is, of course, different from the tubular members, with the result that this unsymmetrical arrangement results in creating in the tubular member different temperatures 20 around the element, which results in undue warping of the device.

In accordance with my invention, the foregoing difficulties are overcome by the provision of a soot-blowing element which is 25 symmetrical, as respects its outer surface, about the axis of the element, thereby producing uniform temperatures around the element.

My invention will best be understood by 30 reference to the accompanying drawings, in which I have illustrated a number of forms of my invention, and in which Figure 1 is a vertical cross-section taken through a steam boiler with the soot-blowing element embodying my invention located above the boiler tubes; Fig. 2 is a fragmentary section, partially in elevation, illustrating one form of soot-blowing element made in accordance with my invention; Fig. 3 is a side view of Fig. 2; Fig. 4 is a longitudinal section through a portion of a soot-blowing element, illustrating a modified form of my invention; Fig. 5 is a cross-section through Fig. 4; Fig. 6 is a sectional view of a soot-blowing element embodying a still further modified form of

my invention; Fig. 7 illustrates a further modification, and Fig. 8 is a view similar to Fig. 7 but illustrating the sections welded together.

Like reference characters indicate like 55 parts throughout the various views.

Referring, now, to the drawings, in which certain forms of my invention are illustrated, and first to Figs. 1, 2 and 3, 10 are the upper steam and water drums of a double boiler in connection with which I have illustrated my invention, and 11 are water tubes in staggered arrangement from top to bottom presenting aisles 12 through which a cleaning fluid may pass. The setting of the boiler is indicated 60 generally at 13. A soot-blowing element, indicated generally at 14, is located above the water tubes and passes through an opening 15 in one of the side walls, fluid under pressure, such as steam, being supplied to the 65 soot-blowing element by a pipe 16. In the form shown, the soot-blowing element is rotated by a grooved wheel 17, over which passes an operating chain 18. An air-tight joint is formed between the pipe 16 and the 70 soot-blowing element 14 at 19, which permits 75 rotary movement of the soot-blowing element relatively to the supply pipe in a well-known manner. The soot-blowing element comprises sections of pipe 20, preferably 80 separately formed and screw-threaded at their ends, as at 21, the adjacent ends of two sections being connected by a separately 85 formed cylindrical section 22, which, in the form shown in Figs. 2 and 3, is formed with a wall sufficiently thick and of a material 90 sufficiently hard so that a jet opening 23 may be formed directly in the wall of the section 22 without its being subjected to excessive erosive action of the fluid under pressure 95 which is ejected therefrom. The soot-blowing element is preferably supported on the upper row of boiler tubes by brackets 24, provided with openings 24^a through which the soot-blowing element passes, each bracket 24 being clamped to one of the boiler tubes by a strap 25 and by suitable nuts 26, as best shown in Fig. 2.

In the form of my invention illustrated in Figs. 4 and 5, the walls of the section 22^a are 100

made thinner than in the arrangement shown in Fig. 2, and the material from which it is made need not be hardened to the same extent as in the arrangement shown in Fig. 5. 2. The section 22^a is preferably generally elliptical, as best shown in Fig. 5, and one portion thereof is provided with a cup-shaped recess 27 in which is received a member 28 formed of erosion-resisting material 10 and is provided with a jet opening 29 registering with an opening 30 formed in the member 22^a.

In the form shown in Fig. 6, the walls at one side of the member 22^b are thickened, 15 as at 31, and provided with a cup-shaped recess 32 in which is received a member similar to the member 28 shown and described in connection with Fig. 4, and which needs no further description.

23 In the arrangement illustrated in Fig. 7, the intermediate section 22^c is provided with an opening 33, preferably slightly inclined inwardly, in which is received a member 34 formed of hardened material and extending 25 inwardly past the wall of the member 22^c, the member 34 extending outwardly, flush with the outer surface of the member 22^c. By confining the jet openings within the outer surface of the tubular element, and 30 forming the element as described, the jet openings are surrounded by walls thicker than the normal thickness of the tubular walls of the element, and the exterior outline of any cross-section through the element, 35 and at right angles to the axis thereof, is symmetrical with reference to the axis of said element.

When the soot blowing element is made practically symmetrical about its axis, and 40 the Venturi nozzles kept substantially or entirely inside of the enlarged part of the element pipe in which the nozzle is formed, as illustrated, the tendency of the element to warp is very much lessened.

45 By forming the inner orifices of the jet openings outside of the interior surface of the tubular members 20, as illustrated, there are no parts which project into the interior of the tubular element to obstruct the flow 50 of steam. Furthermore, the outer orifices of the jet openings are preferably located outside of the outer surfaces of the tubular elements.

Should there be any tendency of the nozzle 55 pieces 22 to loosen, the same may be welded to the adjacent ends of the pipe sections 20 by autogenous welding, as at 35 in Fig. 8. Furthermore, the nozzle pieces may, if desired, be forced over the outside of a continuous pipe, the nozzle pieces welded to the pipe by autogenous welding, and the orifices then drilled through the nozzle pieces and the pipe after the attachment is made.

60 By surrounding the Venturi nozzles which 65 expand outwardly with walls having a great-

er depth or thickness than the normal thickness of the soot-blowing element, and by confining the outer portions and the inner portions of the openings or nozzles within the outer and inner portions of the element, no 70 projections are formed outside of the element which would become heated by the hot gases to which it is subjected, thereby causing warping of the element, and no projections are formed inside of the element which would 75 interfere with the flow of steam through the element.

I claim:

1. A tubular soot-blowing element comprising aligned tubular sections connected by shorter tubular sections thicker than and concentric with the first, the shorter sections only being provided with jet openings freely exposed to the space surrounding said element, said openings being surrounded by walls of greater depth than the normal thickness of the walls of the first-mentioned sections, the exterior outline of any cross-section through said element at right angles to the axis thereof being substantially symmetrical 80 with reference to the axis of said element.

2. A tubular soot-blowing element comprising aligned tubular sections connected by shorter tubular sections having a greater diameter and walls of greater depth than those of the first named sections and provided with jet openings freely exposed to the space surrounding said element, the exterior outline of any cross section through said element at right angles to the axis thereof being substantially symmetrical with reference to the axis of said element, and the inlets of said openings being located outside of the inner surface of the major portion of said tubular element.

3. A tubular soot-blowing element provided with a plurality of jet openings freely exposed to the space surrounding said element, the walls surrounding said openings being of greater depth than other parts of the tube, and the outer surface of said element being substantially symmetrical with respect to the axis thereof, and the inlets of said openings being located outside of the inner surface of the major portion of said tubular element.

4. A tubular soot-blowing element comprising aligned tubular sections connected by shorter tubular sections having a greater diameter and walls of greater depth than those of the first named sections and provided with jet openings freely exposed to the space surrounding said element, the exterior outline of any cross section through said element at right angles to the axis thereof being substantially symmetrical with reference to the axis of said element, the inlets of said openings being located outside of the inner surface of the major portion of said tubular element and the outlets of said openings be-

ing located flush with the outer surfaces of said tubular element.

5. A tubular soot-blowing element having jet openings in the form of outwardly expanding nozzles spaced along its length, said nozzles being located in enlarged parts of the element and inside of the exterior thereof, the exterior outline of any cross section through said element at right-angles to the axis thereof being substantially symmetrical with reference to the axis of said element, the inlets of said nozzles being located outside of the inner surface of said element.

6. A tubular soot-blowing element having outwardly expanding jet openings spaced along its length, said jet openings being located in enlarged parts of the element and surrounded by walls thicker than the normal thickness of the walls of said element, the exterior outline of any cross section through said element at right-angles to the axis thereof being substantially symmetrical with reference to the axis of said element.

7. A tubular soot-blowing element having outwardly expanding jet openings spaced along said element and surrounded by walls of greater length than the normal thickness of the walls of the tube, the outlets and inlets of said openings being confined within the outer and inner surfaces, respectively, of said tubular element, the exterior outline of any cross-section through said element at right angles to the axis therof being substantially symmetrical with reference to the axis of said element, and means for rotating said element.

8. A tubular soot-blowing element having jet openings spaced along said element and surrounded by walls of greater depth than the normal thickness of the walls of the element, the outlets and inlets of said openings being confined within the outer and inner surfaces, respectively of said tubular element.

9. A tubular soot-blowing element comprising aligned tubular sections connected by shorter tubular sections thicker and of greater diameter than the first and concentric therewith, the shorter sections only being provided with outwardly expanded openings surrounded by walls of greater thickness than the normal thickness of the walls of the first mentioned sections, the exterior outline of any cross section through said element at right angles to the axis thereof being substantially symmetrical with reference to the axis of said element.

ISAAC HARTER.

CERTIFICATE OF CORRECTION.

Patent No. 1,745,484.

Granted February 4, 1930, to

ISAAC HARTER.

It is hereby certified that error appears in the printed specification of the above numbered patent requiring correction as follows: Page 3, line 27, claim 7, for the word "length" read "depth"; and that the said Letters Patent should be read with this correction therein that the same may conform to the record of the case in the Patent Office.

Signed and sealed this 8th day of April, A. D. 1930.
